Filed May 7, 1965, Ser. No. 85,180

Term of patent 14 years

(Cl. D72—1)

FIG. 2

FIG. 3

FIG. 1 is a view in side elevation of a warning lamp showing my new design,

FIG. 2 is a corresponding top plan view,

FIG. 3 is a view of the lamp in rear elevation, and

FIG. 4 is a sectional view on the line 4—4 of FIG. 3.

The figures of the drawing are lined to indicate areas of contrasting color.

The side and front not shown are substantially the same as the side and rear shown in FIGS. 1 and 3, respectively.

The broken line representation of a fragment of a support pole in FIGS. 1 and 3 is for purposes of illustration only.

I claim:

The ornamental design for a warning lamp, substantially as shown and described.
